(57) **CLAIM**

The ornamental design for a box with nine cubical puzzle pieces, as shown and described.

DESCRIPTION

FIG. 1 is a perspective view of a box with an open lid and nine cubical puzzle pieces contained therein showing my new design;

FIG. 2 is a perspective view thereof with the lid closed;

FIG. 3 is a rear elevation view thereof;

FIG. 4 is a right side elevation view thereof, the left side elevation being a mirror image thereof;

FIG. 5 is a bottom plan view thereof;

FIG. 6 is a top front perspective view of a first one of the cubical puzzle pieces shown in FIG. 1;

FIG. 7 is a bottom rear perspective view of the cubical puzzle piece of FIG. 6;

FIG. 8 is a top front perspective view of a second one of the cubical puzzle pieces shown in FIG. 1;

FIG. 9 is a bottom rear perspective view of the cubical puzzle piece of FIG. 8;

FIG. 10 is a top front perspective view of a third one of the cubical puzzle pieces shown in FIG. 1;

FIG. 11 is a bottom rear perspective view of the cubical puzzle piece of FIG. 10;

FIG. 12 is a top front perspective view of a fourth one of the cubical puzzle pieces shown in FIG. 1;

FIG. 13 is a bottom rear perspective view of the cubical puzzle piece of FIG. 12;

FIG. 14 is a top front perspective view of a fifth one of the cubical puzzle pieces shown in FIG. 1;

FIG. 15 is a bottom rear perspective view of the cubical puzzle piece of FIG. 14;

FIG. 16 is a top front perspective view of a sixth one of the cubical puzzle pieces shown in FIG. 1;

FIG. 17 is a bottom rear perspective view of the cubical puzzle piece of FIG. 16;

FIG. 18 is a top front perspective view of a seventh one of the cubical puzzle pieces shown in FIG. 1;

FIG. 19 is a bottom rear perspective view of the cubical puzzle piece of FIG. 18;

FIG. 20 is a top front perspective view of a eighth one of the cubical puzzle pieces shown in FIG. 1;

FIG. 21 is a bottom rear perspective view of the cubical puzzle piece of FIG. 20;

FIG. 22 is a top front perspective view of a ninth one of the cubical puzzle pieces shown in FIG. 1; and,

FIG. 23 is a bottom rear perspective view of the cubical puzzle piece of FIG. 22.
